CLAIM

We claim the ornamental design for an automotive vehicle wheel, as shown and described.

DESCRIPTION

FIG. 1 is a perspective view of an automotive vehicle wheel, of the new design;

FIG. 2 is a side elevation view thereof;

FIG. 3 is a top plan view thereof;

FIG. 4 is a rear elevation view thereof;

FIG. 5 is a bottom plan view thereof;

FIG. 6 is a front elevation view thereof; and,

FIG. 7 is a back elevation side view thereof.

The broken lines depict portions of the automotive vehicle wheel that form no part of the claimed design.

1 Claim, 5 Drawing Sheets
